UNITED STATES PATENT OFFICE.

GASPAR B. VERGARA, OF NEW YORK, N. Y., ASSIGNOR TO REMINGTON TYPEWRITER COMPANY, OF ILLION, NEW YORK, A CORPORATION OF NEW YORK.

AUTOMATIC TYPE LIFTING AND LOWERING DEVICE FOR PORTABLE TYPEWRITERS.

Application filed June 17, 1926. Serial No. 116,504.

This invention relates generally to portable typewriters such as are readily carried in a case when not in use, the invention having more particular reference to a novel style of 5 automatic type lifting and lowering device for portable typewriters.

The invention has for an object the provision of a device of the sort described of simple construction and novel arrangement 10 of parts.

For further comprehension of the invention, and of the objects and advantages thereof, reference will be had to the following description and accompanying drawings, and 15 to the appended claims in which the various novel features of the invention are more particularly set forth.

Fig. 1 is a side elevational view of a portable typewriter and carrying case, illustrating 20 the machine in a closed position therein, the cover of the carrying case being partly broken away so as to show more clearly my improved device.

Fig. 2 is a similar view, showing the cover 25 of the carrying case partly removed.

Fig. 3 is a fragmentary sectional view taken on the line 3—3 of Fig. 4.

Fig. 4 is a fragmentary inside view of the cover of the carrying case illustrating parts 30 of my improved device attached thereto.

Fig. 5 is a similar view to that shown in Fig. 3, illustrating my improved device in a disengaged position.

Fig. 6 is a fragmentary top plan view illustrating the type lowering mechanism as used 35 in combination with my improved device.

Fig. 7 is a longitudinal sectional view taken on the line 7—7 of Fig. 6.

Fig. 8 is a transverse sectional view taken 40 on the line 8—8 of Fig. 6.

Fig. 9 is an enlarged sectional view taken on the line 9—9 of Fig. 4.

Fig. 10 is a side elevational view of a portable typewriter, with the side plate partly 45 broken away so as to expose certain interior parts.

The typewriter illustrated in the drawings is the well known Remington portable machine and is designated as a whole by the 50 numeral 10. Said machine is provided with a lever 11 fixed to the rod or rock shaft 12 and having attached to its free extremity a knob 13, extending through an arcuate slot 14, located in the side plate 15 of the portable

typewriter 10. Crank arms 16 are secured 55 to the rod 12 and have pivotally connected to their free ends links 17, which in turn are pivotally connected to ears 18, depending from the combined lifting plate and support or segment member 19, providing a means of 60 moving the said segment member 19 so as to lift the type bars 20 when the said lever of crank arm 11 is swung from the position designated by the reference numeral 21, it being understood that the portable typewriter 10 cannot be operated when the type bars 20 are lowered as designated by the reference numeral 22. The member 19 and the 65 train of mechanism for lifting and lowering the type system to expand the machine for use and to compact it so that it may be contained within its case, preferably correspond 70 with the construction shown in the patent to Barney No. 1,544,204, dated June 30, 1925.

The carrying case element, cover or top 75 23 is adapted to enclose the sides, ends and top of the typewriter 10, and has screwed or otherwise attached to it at the rear thereof a flanged member 24 adapted to engage and operate a projecting member as hereinafter 80 described. A hasp or catch 26 is pivoted to the front portion of the cover or case part 23, said hasp being adapted to engage or cooperate with a keeper (not shown) secured on the support or base 25. The base 25 and 85 the cover-like element 23 of the carrying case cooperate so as to entirely enclose the said typewriter and when secured together permit the machine to be carried or transported readily and without injury. The base 90 25 provides a convenient support for the machine when it is in use. At such times it will be understood the cover part is entirely removed, separated or detached from the other element or part of the case, namely, 95 the base part 25. In order to secure the two cover parts or elements 23 and 25 together there are provided in addition to the hasp and keeper at the front, additional elements at the back, which are not shown herein but 100 are of well known construction. These additional securing devices or elements comprise prongs projecting from the rear of the base and adapted to inter-lock with recessed metal fasteners fixed to the cover. The securing devices at the rear and front, whereby the two detachable elements of the carrying case may be secured and locked together, are

preferably of the construction disclosed in the patent to Holden No. 1,507,355, dated September 2, 1924.

The above described construction is common to portable typewriters of the Remington style such as now generally marketed and used. It is to be understood that the keys 27 cannot be operated when the type bars 20 are in a lowered position, which position is necessary in order to place the carrying case member or top 23 over the portable typewriter 10. In some instances portable typewriters have been rendered inoperative and have needed repairs due to the fact that persons have endeavored to operate the machine without first raising the type bars 20 by means of the knob or finger piece 13.

As herein shown my invention as related to the automatic lifting of the type bars 20 when the above mentioned and described carrying case top 23 is removed, embodies an extended member or head 30 provided with a pointed extremity 31, the head or member 30 being fixed to one extremity of the rod or lever 32 and forming a head at the rear end of said lever. The lever or member 32 is pivoted or fulcrumed at or near its center to the block or bearing 33 fixed to and projecting inward from the plate 39. The movement of the extended element or lever 30 is limited by the stirrup-like guide 31' attached to the side of the plate 39, and it has fixed to its free extremity a knob 34, positioned in an aperture 35, formed in the side of the carrying case top 23. The construction permits the disengagement of the extended member 30 from a pin or projection 36 extending outward from the above mentioned knob 13, when the said knob 34 is pressed or forced inward, as clearly shown in Fig. 5 of the accompanying drawings. When the finger piece or knob 34 is thus pressed inward it will render my improved lifting device inoperative when the carrying case 23 is removed from the typewriter. A coiled spring 32^a normally maintains the lever member 32 in the Fig. 3 position with its rear arm engaged with and arrested by the stop and guide member 31', said spring being overcome by the finger piece 34 when it is pressed in. The bell crank 37 is pivotally supported on the pin 38 which is fixed to and projects from the plate 39. The coiled spring 40 is positioned or wound on the pin 38, and is adapted to normally hold the bell crank 37 against the stop 37^a, so that the cam shaped face 41 of the bell crank 37 is in line with or provides an extension of the tapered side 42 of the element 30. The member or lever 32 and the parts carried thereby, together with the lever or bell crank 37 and associate parts, are mounted on and removable with the plate 39 which is detachably secured by screws 39^a to

the inner face of the right-hand side wall of the case member or top 23.

The above described construction is such as will permit the head 30, normally engaged at its face or tapered side 42 with the above mentioned extension or pin 36 of the said knob 13, to partly force the knob 13 in the slot 14 as the carrying case cover is partly removed from the portable typewriter. Upon further lifting or removal of the carrying case cover, the cam shaped face 41 of the bell crank 37 will engage the pin or extension 36, and will force the knob 13 further across the slot 14. The camming or forcing of the pin 36 and knob or finger piece 13 by the cam faces 42 and 41 during the lifting of the cover as described, swings the crank arm 11 and rocks the shaft 12, thereby swinging the crank arms 16 from the dotted line position indicated at 21 in Fig. 10 to the upright position. This movement of the crank arms raises the links 17, causing them to act on the extensions or ears 18 to lift the type bar lifting frame or support 19 from the lower dotted line position to the upper full line position in Fig. 10, with the result that the machine is expanded, the type bars 20 being elevated as shown into position to be actuated by their associate printing keys 27. This expansion of the machine and lifting of the type bar system is automatically effected, as will be seen, by the relative movement of the two parts of carrying case, that is, by the removal or detachment of the top, cover or case part 23 from the base, support or case part 25. The intermediate stage of the cover lifting or removal is clearly shown in Fig. 2 of the accompanying drawings. During the lifting operation it will be understood that the cam shaped face 41 of the bell crank 37 will engage against the stop 43, attached to and extended from the plate 39, this occurring during the latter part of the lifting movement or removal of the cover.

As herein embodied my improved device, as related to the automatic lowering of the type bars 20, when the above mentioned and described carrying case cover 23 is placed on the said portable typewriter, embodies an engaging member 45, provided with a flanged element 46, bent or formed upward therefrom at a right angle thereto, and provided with extended elements 47 having formed or cut therein elongated slots 48, adapted to be engaged by guide pins or extended members 49 having heads and secured to the base plate 50' which in turn is screwed or otherwise secured to the upper side of the above mentioned base 25, as a means of slidably attaching the said engaging member or slidable plate 45 thereto. The levers 50 are attached, at or near their centers, as at 51, to the plate 50'. Preferably in order to afford a loose connection of the

levers 50 to the base plate, said levers are formed with elongated holes or slots 50^a (Fig. 6) which engage with the pivotal devices or headed pins 51. The levers 50 are 5 pivotally attached, at their outer extremities, as at 52, to the extended elements 47 of the engaging member 45. The free extremities or inner ends 53 are positioned so as to engage with a crank pin 54, attached 10 or fixed to about the middle of the above mentioned rod or rock shaft 12. The above described construction is such as will permit the above mentioned flanged member 24 when the carrying case cover 23 is placed 15 over the portable typewriter, to force or slide the engaging member 45 which will cause the levers 50 to assume the dotted line position designated by the reference numeral 54' (Fig. 6), so as to pivot or rotate the 20 crank pin 54 and rock the shaft 12, which will lower the type bars 20. The plate 50' is slotted to afford play of said crank pin 54. The lower end portion of the head 30 is cut away as indicated at 42' (Fig. 9) to 25 provide a cam surface which cooperates with the pin 36 during the replacement of the cover to force the head 30 rightward against pressure of the spring 32^a; thus enabling the head to pass over the pin and 30 snap leftward under it when the cover has been brought down over the base. Different stages of this operation are illustrated by dotted lines in Fig. 9.

While I have above described the preferred form, construction and arrangement of the several elements employed, it will be understood that the device is, nevertheless, susceptible of considerable modification, and I therefore reserve the privilege of resorting to all such changes as may be fairly embodied within the spirit and scope of the invention as claimed.

While it is preferred to employ the automatic type bar lifting or expanding mechanism in combination or association with the automatic type bar compressing or compacting mechanism, it will be understood that the two mechanisms or sets of devices may be separately used if desired. In other words, I provide means for lifting the type bars and expanding the machine when the cover is removed or detached from the base of the carrying case, which means in operation are independent of the means for depressing the type bars and compacting the machine automatically when the cover is replaced and attached to the base or other part of the carrying case.

I am aware that devices have hitherto been provided for expanding and compacting the mechanism of typewriting machines by the relative movement of cover parts, but in such prior construction the cover parts were necessarily permanently connected or hinged together, and the train of devices

for actuating the expanding and compacting mechanism, were in part on one section of the cover and in part on the other, such train not being disconnectable at any point. In portable typewriters, as at present employed, it would be highly undesirable to have the cover parts permanently hinged together or connected, as this would interfere with the ease with which the machine could be operated and handled when in working condition out of its case. These objections to prior constructions are overcome by my present invention, since the train of automatic expanding devices is automatically separable, as is also the train of compacting devices, so that the separation or detachment of the cover part of the case from the base part is in no wise interfered with.

It will be seen that by my present invention there are provided automatic means for expanding a typewriting machine when the cover part of its case is lifted and removed, said machine being of the expandable and compactible type and its case having two parts; that said automatic means comprise elements on the cover part which are entirely disconnectable both from the machine itself and from the base part of the case; that with said automatic means there are combined means for automatically compacting the machine when the cover part is replaced; that the last recited automatic compacting means comprise an element on the cover and an element on the base part of the case, which two elements are entirely separable or disconnectable when the two parts of the case are disconnected; that automatic means are provided for expanding the machine when one part of the case is moved relatively to the other part, in combination with means for rendering said automatic means inoperative at will; that in the present instance said last recited means is controlled by a finger piece on the cover part of the case, which, when pressed in preliminary to lifting the cover part, renders the automatic expanding means ineffective; and that in the present instance, the automatic means for expanding the machine raises the type bar system into operative position independently of the printing keys.

What I claim as new and desire to secure by Letters Patent is:

1. A device of the class described, embodying means of raising the type bars of a portable typewriter when the carrying case cover adapted to enclose the said portable typewriter is removed therefrom or opened, said means comprising a train of connections operative to raise said type bars, part of said train being on said cover and wholly disconnectable from the other part of the train when the cover is removed.

2. A device of the class described embodying means of lowering the type bars of

- 4
- a portable typewriter when the carrying case cover adapted to enclose the said portable typewriter is closed or placed thereon, said lowering means comprising a train of operative connections, part of which are on said cover and automatically connect with the other part of the connection when the cover is applied to the machine. 5
3. A device of the class described, embodying means of raising the type bars of a portable typewriter when the carrying case top adapted to enclose the said portable typewriter is removed or opened, and means of lowering the said type bars of the said portable typewriter when the said carrying case top is closed or placed thereon, both of said means comprising trains of connections, one train being automatically broken when the top is removed, and the other train having its parts automatically connected when the top is replaced. 10
4. In a device of the class described, an extended member attached at one extremity of a rod, pivotally attached to a block, said block attached to a plate mounted on the inner side of a carrying case, adapted to enclose a portable typewriter, a knob attached to the free extremity of the said rod, said knob positioned in an aperture formed in the side of the said carrying case, so as to permit the disengagement of the extended member and allow the said carrying case to be opened or removed from the said typewriter without the type bars being lifted to an operative position. 15
5. In a device of the class described, an extended member attached to a rod pivotally attached to a plate mounted on the inner side of a carrying case adapted to enclose a portable typewriter, said extended member provided with a pointed extremity normally engaged with an extension of a device operatively connected to lifting means for the type bars of said typewriter, working in cooperation with the cam shaped face of a bell-crank, so as to lift the said type bars to an operative position when the said carrying case is opened or removed from the said typewriter. 20
6. In a device of the class described, an engaging member provided with a flanged element, said engaging member being slidably attached to the base of a portable typewriter, in combination with a train of connections operative by said flanged element to lower the type bars of the said portable typewriter when the said carrying case is closed or placed thereon. 25
7. In a device of the class described, an engaging member provided with a flanged element and with extended elements, said engaging member being slidably attached to a base adapted to support a portable typewriter, levers loosely attached to the base and pivotally attached to the said extended elements of the said engaging member, said levers being positioned so as to engage a crank pin attached to a rod operatively connected to the type bar lifting mechanism of the said portable typewriter, said flanged element of the said engaging member being moved so as to lower the said type bars when the carrying case cover adapted to enclose the said portable typewriter is placed thereon. 75
8. The combination with an expandible and compactible typewriting machine and a two-part case for enclosing said machine, the two parts of the case being entirely separable, of automatic means for expanding the machine operative from the cover part when the cover part of the case is lifted and removed. 80
9. The combination with an expandible and compactible typewriting machine and a two-part case for enclosing said machine, the two parts of the case being entirely separable, of automatic means for expanding the machine when the cover part of the case is lifted and removed, said means comprising elements on the cover part which are entirely disconnectible both from the machine itself and from the base part of the case. 85
10. The combination with an expandible and compactible typewriting machine and a two-part case for enclosing said machine, the two parts of the case being entirely separable, of automatic means for expanding the machine when the cover part of the case is lifted and removed, said means comprising elements on the cover part which are entirely disconnectible from the machine and from the base part of the case, and means for automatically compacting the machine when the cover part is replaced. 90
11. The combination with an expandible and compactible typewriting machine and a two-part case for enclosing said machine, the two parts of the case being entirely separable, of automatic means for expanding the machine when the cover part of the case is lifted and removed, and means for automatically compacting the machine when the cover part is replaced, said last recited means comprising an element on the cover and an element on the base part of the case, said two elements being entirely separable or disconnectible when the case parts are disconnected. 100
12. The combination with an expandible and compactible typewriting machine and a two-part case for enclosing said machine, the two parts of the case being entirely separable, of means for automatically compacting the machine when the cover part is replaced, said means comprising an element on the cover and an element on the base part of the case, said two elements being entirely separable or disconnectible when the case parts are disconnected. 110
- 130

13. The combination with an expansible and compactible typewriting machine and a two-part case for enclosing the machine, of automatic means for expanding the machine 5 when one part of the case is moved relatively to the other part, and means for rendering said automatic means inoperative at will.
14. The combination with an expansible 10 and compactible typewriting machine and a two-part case for enclosing said machine, the two parts being separable; of automatic means for expanding the machine when the cover part of the case is lifted and removed, 15 and hand-actuated means for rendering said automatic means ineffective when the cover part is lifted.
15. The combination with an expansible and compactible typewriting machine and a 20 two-part case for enclosing said machine, the two parts of the case being completely separable, of automatic means for expanding the machine when the cover part of the case is lifted and removed, and means operative by 25 a finger piece on the cover part for rendering said automatic means ineffective when the cover part is lifted.
16. The combination with an expansible and compactible typewriting machine and a 30 two-part case for enclosing the machine, of
- automatic means for raising the type bar system of the machine into operative position independently of the printing keys when the cover part of the case is lifted.
17. The combination with an expansible 35 and compactible typewriting machine and a two-part case for enclosing the machine, of automatic means for raising the type bar system of the machine into operative position independently of the printing keys 40 when the cover part of the case is lifted, said means comprising a cam device mounted on the cover part and acting against the type bar raising mechanism when the cover is lifted.
18. The combination with an expansible and compactible typewriting machine and a two-part case for enclosing the machine; of automatic means for raising the type bar 45 system of the machine into operative position when the cover part of the case is lifted, said means comprising a cam device acting to operate the type bar raising mechanism when the cover is lifted, said cam device yielding so that it is ineffective when 50 the cover is restored.

In testimony whereof I have affixed my signature.

GASPAR B. VERGARA.
